Attorney,

UNITED STATES PATENT OFFICE.

MICHAEL B. FIELD, OF GLASGOW, SCOTLAND, ASSIGNOR TO KELVIN BOTTOMLEY & BAIRD, LIMITED, OF GLASGOW, SCOTLAND, A CORPORATION OF GREAT BRITAIN.

MARINER'S COMPASS.

1,419,836.

Specification of Letters Patent. Patented June 13, 1922.

Application filed December 20, 1918. Serial No. 267,625.

To all whom it may concern:

Be it known that I, MICHAEL BIRT FIELD, a subject of the King of the United Kingdom of Great Britain and Ireland, and residing at Glasgow, Scotland, have invented a certain new and useful Improvement in Mariners' Compasses, of which the following is a specification:—

My invention relates to improvements in or relating to so-called liquid magnetic compasses, and has special reference to liquid compasses of the navigational type having cards say of 5" diameter and upwards, although my invention is also applicable to liquid compasses of smaller sizes.

With the liquids at present used in liquid compasses the card may be said to be over-damped, that is to say, the fluid drag on the card is so great that the movement tends to become sluggish; to overcome this tendency, it has been customary to use magnetic needles of far higher magnetic moment than is advisable on account of other considerations. With such powerful magnetic needles the moving system is heavy and requires considerable flotation by means of an air-filled dome, or the equivalent, in order to reduce the friction on the pivot. Heaviness of the moving system and large magnetic moment are disadvantageous.

The consequence of the fluid drag upon the moving system is noticeable when the containing bowl is rotated; for example, if the ship steer round in a complete circle, the compass bowl is rotated once. Such rotation sets up movement of the liquid, which, reacting on the card, produces a temporary deviation.

Objects of my invention are, firstly, with a given size of card and bowl, to employ a smaller magnetic moment than has hitherto been practicable, other properties of the compass being the same, or, conversely, with the same magnetic moment as is used at present, to employ a larger sized card without impairing other characteristics of performance of the compass, or, *ceteris paribus*, to provide a compass having a shorter period.

Secondly, with a compass card of a given size, to reduce the effect of turning motion of the bowl in terms of deviation of the card, or conversely, to permit the use of a larger card, other things being equal.

Other objects are to improve the constructional features of the compass and to reduce the weight of the moving system for a given diameter of card.

Additional objects will appear from the following description.

In order to reduce the period, without increasing the magnetic moment, it has been proposed to reduce the moment of inertia of the moving system. I have found, however, that if the diameter of the card and magnetic moment of the moving system remain the same, the maximum reduction of moment of inertia of a well designed moving system permitted by any further modification of design does not result in a very great reduction of the period. I have thus been led to suspect that the rotational motion set up in the liquid by the oscillating card reacts upon the latter in such a manner that the card behaves as though it were loaded with an additional moment of inertia, besides being acted upon by a resisting torque which is at every instant proportional to the angular velocity, that is to say, what is known as a true fluid friction effect.

For example, I find as the result of experimental research that if a card or disc be oscillated about its axis in the liquid besides the drag which would be produced in consequence of true fluid friction effect there is an additional drag the same as would be produced if the card were loaded by an additional moment of inertia, such drag being proportionate to the square foot of the product of the density and the coefficient of viscosity of the liquid, and I find that the amount of the effective additional moment of inertia due to the movement of the liquid is great in comparison with the actual moment of inertia of the moving system I have found, therefore, that in order to arrive at a radical improvement it is necessary to decrease as far as possible by the choice of a suitable liquid the amount of the effective additional moment of inertia. This amount is reduced when the density or the co-efficient of viscosity of the liquid, or both are decreased.

The other properties of the liquid, necessary or advisable, are that it shall be able to withstand without freezing very low temperatures such as are met with in the Arctic

regions, that it shall be able to withstand without boiling or developing an undue vapour pressure the temperatures met with in the equatorial regions of the earth, and that it shall be transparent, colourless, and inert in the presence of metals, and preferably, though not necessarily, of paints.

A suitable liquid has been found in the hydrocarbon hexane, which according to the 10 Smithsonian Physical Tables, published by the Smithsonian Institution, 1903, has, at a temperature of about 23° C., a co-efficient of viscosity of approximately .0033 in C. G. S. units and a density of about .663. I 15 do not confine myself, however, to any one liquid or to any one series. For the purpose of the invention the chemical constitution of the liquid employed is relatively of no moment; a liquid is suitable 20 according as it possesses the essential physical properties above indicated, it being understood that the product of the density and co-efficient of viscosity of the liquid at a temperature of from 20° to 25° C., 25 should not be more than say one fourth of the product of the density and co-efficient of viscosity of a well known standard alcohol and water mixture, the approximate density of which mixture, within the range 30 of temperatures stated, is .95 and the approximate co-efficient of viscosity of which, within the range of temperatures stated, is .025 in C. G. S. units. (See Smithsonian Physical Tables).

35 The liquid which I prefer to use is a volatile saturated hydrocarbon having the formula C_nH_{2n+2} the product of whose density and co-efficient of viscosity, at a temperature between about 20° C. and 25° 40 C., is not more than about one fourth of the product of the density and co-efficient of viscosity of the usual alcohol and water mixture.

Certain liquids, which are otherwise suitable on account of their low viscosity, may be 45 objectionable on account of being too volatile or of exercising a destructive action on the usual jointing means provided in a compass bowl.

50 I provide, therefore, a chemically indestructible joint or joints for the container for the liquid and seal such joint or joints by means of liquid.

The sealing liquid may be, for example, 55 glycerine, which is inert on such packing material as rubber, which is not miscible with the liquid contents of the bowl, and which is not liable to be frozen.

In constructing the moving system I have 60 aimed at making the moment of inertia as small as possible, and the whole system as light as possible, and in so doing I have arrived at structural improvements now to be described with reference to the accompanying drawing in which Fig. 1 is a ver-

tical section through the compass bowl, Fig. 2 a plan of the card and Fig. 3 a sectional detail view showing the arrangement for ensuring equilibrium of pressure on the interior and exterior of the joints.

70 Heretofore, it has been usual to arrange the needles as parallel chords of a circle. Now, I arrange the needles 1 parallel to a diameter, but I dispose them as shown so that the shorter needles are nearer to the 75 centre of the card 2 than the longer needles and so that the ends of the needles, or rather the poles of the needles, lie upon opposed V-shaped figures, the apices of which are at or near the centre; thus, all north 80 poles lie upon a V, the angle of which is approximately 60 degrees, while all south poles lie upon a diametrically opposed V of the same angle.

85 It is known that considerable advantages accrue from the disposition of two parallel needles, the north poles of which and also the south poles subtend angles of 60 degrees at the centre of the card, but I am not aware that it has been proposed to arrange 90 a plurality of needles on each side of a diameter in such a manner that the poles of each pair comply with this condition. The arrangement I have adopted is not only favourable from the magnetic point of view, 95 but it further provides a smaller moment of inertia than when the needles are arranged as usual heretofore as parallel chords of a circle.

100 By the use of the described arrangement of needles, and by the choice of a suitable liquid, I am enabled to use needles of much smaller weight than has been considered practicable heretofore for a liquid compass of the same diameter of card, and hence 105 with a smaller size of card, say, from 4" downwards, no flotation devices need be added. For larger sized cards, as, for example, for a 6½" card, a certain amount of flotation is desirable.

110 Instead of employing the usual heavy metallic air-filled dome, in order to provide flotation without adding materially to the mass of the moving system, I prefer to employ a hollow glass float or floats, say two 115 small blown glass spheres 3 or, the equivalent with exceedingly thin walls which may be attached to the moving system by means of a light wire cage 4, and are arranged as near to the pivot as is 120 practicable.

The central pivot stem 5 is shown as supported by an apertured platform 6 of mica resting on an annular shelf 7 secured to the interior vertical wall 8 of the compass bowl. 125 I provide an annular chamber 9 surrounding the vertical wall 8, which latter is provided below the level of the platform 6 with apertures 9' establishing communication between the spaces interior to and exterior to the 130

vertical wall 8 and permitting transference of air bubbles from the inner chamber to the chamber 9.

The annular chamber 9 is in turn accommodated in a chamber 10 containing a sealing fluid which does not readily volatilize, which is preferably immiscible with the liquid in which the card is poised, and which is preferably inactive on the rubber or other 10 packing interposed between the metallic bezel ring 11 and the glass cover 12 and between the lower ring 13 and the glass bottom 14 (it being understood that the packing rings 15 which are exposed to the action 15 of light fluid, hexane, for example, are of some material such as lead which is not liable to be attacked by hexane or the like).

As best seen in Fig. 3, the outer wall of the annular chamber 9 is provided with apertures closed by flexible diaphragms 10', so that equilibrium of pressure on the interior and exterior of the joints 15 may be maintained.

A screw plug 16 preferably fitted with a 25 suitable packing washer and entered into an apertured socket fixed to the wall 8 in register with a plug 17 also fitted with a packing washer and entered into an apertured socket fixed to the exterior wall of the 30 chamber 10 permits of introduction of liquid to the bowl and replacement of liquid to compensate for leakage.

18 denotes an annulus soldered to the wall of the bowl and bearing degree markings.

35 The annulus 18 being below the plane of the card 2, the markings thereon are not obtrusive when the card is being observed by the steersman or otherwise read for taking magnetic directions.

40 On the other hand, when the compass is used in conjunction with an azimuth mirror, the markings on the annulus 18 fall upon the line of sight of an observer looking down into the compass bowl at an angle of, 45 say, 60 degrees to the horizontal.

The rubber line or point 19 is shown as supported by the wall 8. It will thus be understood that the wall 8 carries the whole essential mechanism of the compass, that is 50 to say, the platform 6 and therewith the cen-

tral support of the card, the rubber point, and the compass card, and all these may be inserted in place as a single unit, care being taken that the rubber line is properly orientated with regard to the axis of gimbal. 55

What I claim is:—

1. A magnetic compass comprising a card and a chamber containing a liquid medium in which said card is poised, said medium being a volatile saturated hydrocarbon having the formula C_nH_{2n+2} the product of whose density and co-efficient of viscosity, at a temperature between about 20° C. and 25° C., is not more than about one fourth of the product of the density and co-efficient of viscosity of the usual alcohol and water mixture. 60

2. In combination, a magnetic compass card, and a plurality of needles carried by said card on each side of the center, said 70 needles on each side of the card being arranged parallel to a diameter of the card with the poles of said needles located upon imaginary opposed V-shaped figures which converge towards the centre of the card and 75 whose apices are substantially at the centre of the card, the angle of each V-shaped figure being substantially 60°, the length of the needles increasing proportionately to their distance from the centre of the card. 80

3. In a magnetic compass, the combination of a chamber containing a liquid, packing rings at the joints of the walls of said chamber, a card poised in said liquid, a second chamber containing a sealing liquid and surrounding said first mentioned chamber, a third chamber intermediate said first and second mentioned chambers, said third chamber communicating with the first chamber, the outer wall of said third chamber having 90 apertures, and flexible diaphragms closing said apertures. 85

In testimony whereof I have signed my name to this specification in the presence of two subscribing witnesses.
